UNITED STATES PATENT OFFICE.

JAMES C. DAVIS, OF HINSDALE, ILLINOIS, ASSIGNOR TO AMERICAN STEEL FOUNDRIES, OF NEW YORK, N. Y., A CORPORATION OF NEW JERSEY.

METHOD OF DRYING MOLDS.

967,616.

Specification of Letters Patent. Patented Aug. 16, 1910.

Original application filed September 9, 1907, Serial No. 391,961. Divided and this application filed December 3, 1909. Serial No. 531,195.

To all whom it may concern:

Be it known that I, JAMES C. DAVIS, a citizen of the United States, residing at Hinsdale, in the county of Dupage and State of Illinois, have invented certain new and useful Improvements in Methods of Drying Molds, of which the following is a specification.

My invention relates to improvements in the methods used for heating and drying molds employed for the casting and founding of metal bodies or parts. The usual and ordinary method or process of drying molds is to lift the mold on to a car and run the car and mold into a drying oven to which heat is applied by coke, coal, gas, or other suitable fuel. It has been found, however, that molds transported and treated in this manner are likely to be shaken up and injured by their handling, and although the mold is dried hard on its surface its interior is likely to be left moist.

It is the object of my invention to provide a process for heating and drying molds without transporting them and making the drying of the mold complete throughout the entire body of sand. By my improved method the heat is supplied to the interior of the sand of the mold by means of steam or other suitable heating element circulating through or fed to pipes embedded in the sand. Preferably the cope and drag each has a pipe coil or lengths of pipe in its sand, the ends of the pipe being joined when the cope is superposed on the drag, whereby the steam admitted to the pipe of one passes or circulates to the other. If desired, of course, the supply and circulation of steam and the pipes of the two parts of the mold may be quite distinct and separate.

In carrying out my improved method the drying element, preferably steam, is brought to the mold instead of the latter being conveyed or carried to the drying chamber, as is usually done, and in carrying out my method the heat is applied to the inside of the body of sand, and consequently the mold is sure to be thoroughly dried throughout and not "skin dried."

In the accompanying drawing, forming a part of this specification, I have illustrated a simple and convenient apparatus for carrying on this process, and in this drawing—Figure 1 is a plan view of the cope of the

mold; Fig. 2 is a plan view of the drag; 55 Fig. 3 is a side elevation of the parts of the mold assembled; and Fig. 4 is an elevation of the right-hand end of the assembled mold shown in Fig. 3.

Referring now to this mold suitable for 60 carrying on my improved process, it will be noticed that the cope 10 is of the usual and ordinary construction, and has embedded in its sand the lengths of pipe 11, 12, 13, 14, and 15, united by elbows of the ordinary 65 form. The pipe 10 extends outwardly through one end of the cope, and the protruding portion is equipped with a steam inlet valve 16. The pipe 15 extends through the other end of the cope and is connected 70 by an elbow with a short length of pipe 17 having at its end one element 18 of a union which provides means for disengageably connecting the pipe 17 with a similar pipe 75 of the drag. It will be noticed from Fig. 1 75 that the pipes within the sand of the cope provide three lengths substantially the full longitudinal dimension of the cope, whereby a complete and thorough heating of its sand may be secured.

The drag 19 has embedded in its sand a pipe 20 which protrudes through the end of the drag and is connected by an elbow with a short pipe 21 on the free end of which is the other member 22 of the union 18—22. 85 The other end of pipe 20, by means of a cross-pipe 23, connects with another longitudinal pipe 24, which in turn by a short inclined cross-pipe 25 is joined to another lengthwise pipe 26 in a plane somewhat below the pipes 20 and 24. Pipe 26, by means of the connecting pipe 27 is joined to the long pipe 28 which projects through the right-hand end of the drag and is equipped 90 with a steam outlet or drip valve 29. It 95 will be noticed that owing to these four long pipes 20, 24, 26, and 28 a thorough and complete drying of the sand of the drag may be readily effected.

After the mold cavity 30 has been formed 100 in the sand, the cope with its pipes is placed upon the drag and fastened thereto in any approved manner, as is indicated in Fig. 3. Pipes 17 and 21 are disengageably connected by the union 18—22, whereby the pipes 105 of the cope and drag are joined to form a continuous conduit or tube for the passage of steam through or admission of steam to

the parts of the assembled mold. Steam or other suitable heating element is supplied to the pipes by the opening of the valve 16, and may be allowed to exhaust through the valve 5 29 or the water of condensation permitted to drip through such latter valve. Owing to the fact that the steam pipes are buried within the body of sand forming the mold, it is thoroughly heated and dried throughout, 10 no skin drying alone being effected. Inasmuch as the heating element such as steam may be readily conducted to the mold in any position or location, it is unnecessary to transport the mold to a drying chamber, 15 thereby risking injury to the carefully fashioned mold. As will be obvious, a disconnection between the pipes 17 and 21 may be readily effected, whereupon the cope can be easily lifted from the drag.

20 To those skilled in the art it will be apparent that the precise number of pipes or their location or disposition within the sand is quite immaterial, and that the structure shown in the drawing and described above 25 is merely set forth as one way in which this method can be advantageously carried out. The disposition of the steam pipes within the sand of the mold, as will be readily understood, may be varied to correspond with 30 different shapes of mold cavities, but in any case the pipes would be buried within the sand and effect the drying operation as described above, that is, from the interior of the sand outwardly.

35 I have deemed it unnecessary to illustrate the steam generator or other source of supply of the heating element, but it is to be understood that the pipe 11 is intended to

be connected by any suitable means with a boiler generating steam or other source of 40 supply of a suitable heating element.

This application is a division of my former application Serial No. 391,961, filed September 9, 1907.

I claim:

1. The method of drying a mold which consists in passing a heating medium through the material of the mold between the mold cavity and the exterior of the mold and maintaining the heating medium out of 50 direct contact with the material of the mold, substantially as described.

2. The method of drying a mold which consists in passing steam through the material of the mold between the mold cavity and the exterior of the mold and maintaining the steam out of direct contact with the material of the mold, substantially as described.

3. The method which consists in drying 60 a mold by radiation from a heating medium located in the body of the mold exterior of the mold cavity and out of direct contact with the material of the mold, substantially as described.

4. The herein described method of drying molds which consists in circulating a heating medium through the material of the mold between the mold cavity and the exterior of the mold and out of direct contact 70 with the material of the mold, substantially as described.

JAMES C. DAVIS.
